Primary Examiner — Susan Bennett Hattan*Assistant Examiner* — Leanne Was(74) *Attorney, Agent, or Firm* — Muirhead and Saturnelli, LLC(57) **CLAIM**

The ornamental design for an optics mount, as shown and described.

DESCRIPTION

FIG. 1 is a perspective view from above showing the new design;

FIG. 2 is a perspective view from below thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines showing unclaimed environment form no part of the claimed design.
